(57) **CLAIM**

The ornamental design for an air block for respirator, as
shown and described.

DESCRIPTION

FIG. 1 is a rear perspective view of an air block for respirator
according to the present invention;

FIG. 2 is a right side view of the air block of FIG. 1;

FIG. 3 is a front view of the air block of FIG. 1;

FIG. 4 is a left side view of the air block of FIG. 1;

FIG. 5 is a bottom view of the air block of FIG. 1; and,

FIG. 6 is a top view of the air block of FIG. 1.
